UNITED STATES PATENT OFFICE.

FREDERICK L. G. STRAUBEL, OF GREEN BAY, WISCONSIN.

FILE-CABINET.

1,083,304.

Specification of Letters Patent.

Patented Jan. 6, 1914.

Application filed March 12, 1912. Serial No. 683,312.

To all whom it may concern:

Be it known that I, FREDERICK L. G. STRAUBEL, a citizen of the United States, residing at Green Bay, in the county of Brown 5 and State of Wisconsin, have invented a new and useful Improvement in File-Cabinets, of which the following is a specification.

My invention relates to an improvement in a cabinet with a receptacle in which sheet 10 music, as well as letters and commercial papers, can be filed vertically.

The object of my invention is to provide a means for conveniently filing such sheets or papers and to give ready reference and access to same after having been filed. I attain 15 this object by means of the vertical filing device illustrated in the accompanying drawings in which:—

Figure 1 is a sectional view of the cabinet 20 when closed and showing the interior of one side. Fig. 2 is a sectional view of the same device with the top raised. Fig. 3 is a perspective view of the compressing device.

Similar figures refer to similar parts 25 throughout the several views.

1 is the base, 2 the back, 3 one of the sides, 4 the front, and 5 the cover of the filing cabinet. The cover 5 is hinged at 6 and when 30 open assumes a similar position to that shown in Fig. 2. The front 4 of the cabinet is hinged at the bottom at 7, and at the upper portion of each of the two sides at 8 it has pivotally attached thereto, one on each side, the front ends of connecting rods 9. 10 is a 35 lever attached to the side of cover 5 and is pivotally attached to connecting rod 11.

The arrangement of connecting rod 9 and lever 10 is such that when the cover 5 is raised the front 4 of the cabinet will be 40 thrown forward. The object of this arrangement being to loosen up the contents of the cabinet so that they may be readily inspected. Cover 5 is held open by a bar 12 which is pivotally attached at 13 to the side 45 of the cover and loosely held to the side 3 of the cabinet with a pin which operates in a slot 14 of the bar 12. At the lower end of this slot a notch 15 is made on the upper side and when the cover is raised to its full

height this notch drops on the pin thus holding the top open. 16 is a bar extending to near the front of the cover and by which the lever 12 may be raised from the pin which will allow the cover to be dropped in place.

On the bottom 17 of the cabinet is slidably 50 mounted an adjustable follower 18 against which the inclosed sheets rest. Said follower has a base 19 and a clutch 20 which engages a rod 21 in a slot in the base 17. By means of this clutch arrangement this follower can 55 be placed at any desired point front or back, in the filing cabinet, providing for the filing of a small or a large quantity of sheets as desired.

22 is a compressor which is pivotally attached to the hinged front of the cabinet at 23, and is operated by arms 24 and projections which engage a slot 25 at either side of the cabinet. When the top is open this compressor is forced back against the hinged 70 front 4 of the cabinet. When the cabinet is closed the engagement of the arm 24 with the slot 25 forces the upper part of the compressor forward against the filed sheets, thus compressing them and pushing them out of 75 the way of the descending cover.

The form of the compressor shown here may be varied without affecting my rights, as for instance the arms 24 may be pivotally attached to the sides 3 of the cabinet and 80 only bear against the inside of the hinged front 4 at 23. The compressor is shown here as a flat surface, as a board. It may also be made in the form of a loop of metal or other material.

The cover connection of this cabinet with the hinged front and the sliding follower are similar to the form shown in my Patent No. 812,962 granted Feb. 20, 1906. I therefore do not claim specifically upon these 90 features alone, but

What I claim as new and desire to secure by Letters Patent is:—

1. In a filing cabinet a case having a hinged front, a compressor pivotally attached to the hinged front, arms on either side of the compressor engaging slots in the sides of the case, and so arranged that when

the hinged front is closed the compressor is thrown backward against the contents of the case.

2. In a filing cabinet a case having a hinged front, a compressor pivotally attached to the sides of the case, and adapted to bear against the inside of the hinged front in such manner that when the hinged front

is closed the upper portion of the compressor is forced backward against the contents of the case.

FREDERICK L. G. STRAUBEL.
